(57) CLAIM

The ornamental design for jewelry such as a pendant and the like as shown and described.

DESCRIPTION

FIG. 1 is a perspective view of jewelry such as a pendant and the like showing our new design;

FIG. 2 is a front view thereof;

FIG. 3 is a back view thereof;

FIG. 4 is a left side view with the right side being a mirror image thereof;

FIG. 5 is a top view thereof; and,

FIG. 6 is a bottom view thereof.

The broken line showing of portions of the jewelry such as a pendant and the like forms no part of the claimed design.

1 Claim, 3 Drawing Sheets
